SILT REMOVING HEAD

Charles B. Harp, Los Angeles, Calif.

Application April 23, 1934, Serial No. 721,945

7 Claims. (Cl. 37—78)

This invention relates to a silt removing head adapted to be used in a silt removing system. Silt carrying liquids will deposit silt at quiescent zones, due to settling of the silt. Such quiescent zones are present on the upside of dams in streams, in natural and artificially formed water accumulating basins and other places. In many instances settling chambers are provided for the purpose of separating out some of the silt. Obviously, the accumulated silt must be removed from time to time and this removal should be effected expeditiously, economically and with least disturbance to the remaining water system. In Patent No. 1,777,491 granted to me October 7, 1930, for Method of desilting channels, I have disclosed a hydraulic method of desilting basins. The present invention appertains to silt removing heads which may be used in carrying out such a method whether applied to channels or any basin in which silt may settle.

The objects of this invention are to provide a silt removing head mounted permanently in the bottom of a basin, having any or all of the following features:—structure to prevent clogging of the slush intake openings; structure to provide a slush mixing chamber wherein turbulence of the water and entrained silt is maintained to cause its ready flow into the slush conductors; means to clean the slush conductor intake openings and, if desired, to occlude entrance of slush to the slush conductor, and details of structure contributing to simplicity, compactness, strength and durability of such heads together with ease and certainty of operation.

These objects are accomplished by means of the embodiment of my invention disclosed in the appended description and illustrated in the accompanying drawing, in which:—

Fig. 1 is a section through a silt bed showing my improved head in elevation; Fig. 2 is a vertical section through a fragment of head on an enlarged scale; and Fig. 3 is a section as seen on the broken line 3—3 of Fig. 2.

In order that the subsequent description may be clearly understood, certain terms used are here defined. The term silt is used in a sense inclusive of solids, such as silt, sand, dirt or the like, capable of being entrained in liquids. Slush is the mixture of such silt. Basins are quiescent zones in a body of liquid coextensive or partially extensive therewith and may be either natural, artificial or both.

Referring more particularly to Fig. 1, the bed of a basin is indicated by A. A foundation of cement or the like is denoted by B. The founda-

tion B may range over the area from which silt D is to be removed and a number of heads C may be distributed over the bed and in positions determined to be most effective for removal of silt. The silt removing system is intended to be used intermittently as a deposit of silt has accumulated necessitating removal. Thus, there may be comparatively long periods during which the heads are not in use. Silt may pack around the heads, enter orifices and make the system inoperative unless the heads are designed to prevent lodgment of silt.

In the present invention, protection from lodgment of silt is accomplished by a hood 5 which may be of conical form with the crown or tip at the upper side. The hood 5 may be of sheet metal having at its hem an annular flange 6. Connected to the hood 5 by welding or any other suitable means are stilts 7. These stilts may be metal bars having angular bends so as to have legs which may be disposed perpendicular and form a cage below the hood. They act as a trash rack to prevent entrance of trash into the hood. Stilts 7 may be set in the foundation B to permanently fasten the head in selected position over the bed A.

A slush conductor in the form of a pipe 8 extends along the bed and at each head has a riser 9 which projects centrally into the hood. The top of the riser is enlarged and lateral inlet openings 10 are provided therein, these openings being adjacent the crown of the hood. The top of riser 9 may be closed by a chamber 11 which has depending nozzles 12 directed to project jets of water across the openings 10. Chamber 11 is connected to a conduit 13. The latter is adapted to be connected to a source of liquid under pressure. When water under pressure is passed through conduit 13, jets will be projected by nozzles 12 across inlet openings 10. This will dislodge insoluble material from the latter and in the event flow of water is continued, will prevent entrance of slush making the head inoperative for removal of slush.

Ranging circumferentially about the hood at a point intermediate the top and bottom is a conduit 14 which is connected to a supply line 15 leading to a source of liquid under pressure. Connected to conduit 14 are nozzles 16 positioned to direct fluid inwardly and downwardly in a spiral direction and thus cause turbulence of liquid in the hood.

Below conduit 14 is another circumferentially extending conduit 17 having nozzles or spouts 18a to project water downwardly and outwardly

parallel to the wall of the hood. These spouts are in registration with openings 19 in flange 6 so that jets of water may pass to the outside of the hood at the hem of the latter.

5 Pipes 13, 15 and 18 are preferably separately controlled and pipe 13 may lead to only a selected number of heads C while the pipes 15 and 18 may be connected to all the heads or selected groups of heads as deemed advisable for the particular conditions. Assume that a layer of silt D has accumulated and it is desired to remove it. During accumulation of the silt, the hood 5 will have offered protection to the slush intake and nozzles of the head. The action is initiated by 10 supplying water under pressure to pipes 13, 15 and 18. The water issuing from nozzles 12 will clear inlet openings 10 of an accumulated material. Water jetting from nozzles 16 mixes with the silt, agitates the latter and keeps the liquid 15 under the hood in a state of turbulence. Water issuing from spouts 18a passes into the silt outside of the hood and creates a slush. The water in pipe 13 is next shut off. This frees the inlet 20 openings 10 for intake of slush. Pipe 8 is subjected to a suction pressure thereby drawing slush 25 into the riser 9 and carrying it away. The silt D lowers, and in the vicinity of the head slides downwardly toward the latter.

The entire field zoned with the heads will be 30 cleared of silt. Obviously the floors of shallow basins may be sloped towards the heads to allow easier flow of silt. After removal of silt, the system is closed down and silt again accumulates. The hoods 5 offer protection to the nozzles and 35 intakes against the load of silt as well as shifting banks.

What I claim is:—

1. A silt removing head mounted permanently 40 in the bottom of a basin comprising a hood, means to support said hood in a position with its mouth open mounted permanently in the bottom of a basin, a slush conductor having an intake chamber with inlet openings disposed within said hood adjacent the crown thereof; and a conduit adapted 45 to be connected to a source of liquid under pressure and having means disposed and positioned within said hood to produce turbulence of liquid therein.

2. A silt removing head mounted permanently 50 in the bottom of a basin comprising a hood, means to support said hood in a position with its mouth open mounted permanently in the bottom of a basin, a slush conductor having an intake chamber with inlet openings disposed within said hood adjacent the crown thereof; a conduit adapted 55 to be connected to a source of liquid under pressure and having means disposed and positioned within said hood to produce turbulence of liquid therein; and a conduit adapted to be connected to a source of liquid under pressure and having spouts disposed to direct liquid outwardly from 60 said hood at the hem thereof.

3. A silt removing head mounted permanently 65 in the bottom of a basin comprising a hood, means to support said hood in a position with its mouth open mounted permanently in the bottom of a basin; a slush conductor having an intake chamber with inlet openings disposed within said hood adjacent the crown thereof, a conduit adapted 70 to be connected to a source of liquid under pressure and having nozzles disposed to project liquid across said inlet openings; a conduit adapted to be connected to a source of liquid under pressure

and having means disposed and positioned within said hood to produce turbulence of liquid therein; and a conduit adapted to be connected to a source of liquid under pressure and having spouts disposed to direct liquid outwardly from said hood at the hem thereof.

4. A silt removing head mounted permanently 10 in the bottom of a basin comprising a hood mounted permanently in the bottom of a basin, spaced stilts extending from the hem of said hood to support the latter and forming an annular trash rack; a slush conductor having an intake chamber with inlet openings disposed within said hood adjacent the crown thereof; and a conduit adapted 15 to be connected to a source of liquid under pressure and having means disposed and positioned within said hood to produce turbulence of liquid therein.

5. A silt removing head mounted permanently 20 in the bottom of a basin comprising a hood mounted permanently in the bottom of a basin, spaced stilts extending from the hem of said hood to support the latter and forming an annular trash rack; a slush conductor having an intake chamber with inlet openings disposed within said hood 25 adjacent the crown thereof; a conduit adapted to be connected to a source of liquid under pressure and having means disposed and positioned within said hood to produce turbulence of liquid therein; and a conduit adapted to be connected to a source 30 of liquid under pressure and having spouts disposed to direct liquid outwardly from said hood at the hem thereof.

6. A silt removing head mounted permanently 35 in the bottom of a basin comprising a hood mounted permanently in the bottom of a basin, spaced stilts extending from the hem of said hood to support the latter and forming an annular trash rack; a slush conductor having an intake chamber with inlet openings disposed within said hood 40 adjacent the crown thereof, a conduit adapted to be connected to a source of liquid under pressure and having nozzles disposed to project liquid across said inlet openings; a conduit adapted to be connected to a source of liquid under pressure 45 and having means disposed and positioned within said hood to produce turbulence of liquid therein; and a conduit adapted to be connected to a source of liquid under pressure and having spouts disposed to direct liquid outwardly from 50 said hood at the hem thereof.

7. A silt removing head mounted permanently 55 in the bottom of a basin comprising a conical hood mounted permanently in the bottom of a basin, spaced stilts extending from the hem of said hood to support the latter and forming an annular trash rack; a slush conductor extending axially into said hood and having an intake chamber with inlet openings disposed within said hood adjacent the apex thereof, a conduit adapted to be connected to a source of liquid under pressure 60 and having nozzles disposed to project liquid across and through said inlet openings; a conduit adapted to be connected to a source of liquid under pressure having means disposed and positioned within said hood to direct water downwardly and inwardly toward the axis of said hood to produce turbulence of liquid therein; and a conduit adapted to be connected to a source of liquid of liquid under pressure having spouts disposed to 65 direct liquid parallel to the wall of said hood and outwardly from said hood at the hem thereof.

CHARLES B. HARP.
